Primary Examiner—Terry A. Wallace[57] **CLAIM**

The ornamental design for a liquid cooling stir stick, as shown and described.

DESCRIPTION

FIG. 1 is a front elevational view of the liquid cooling stir stick showing my new design;

FIG. 2 is a top view thereof;

FIG. 3 is a bottom view thereof;

FIG. 4 is a sectional view taken along line 4-4 of FIG. 1; and,

FIG. 5 is a sectional view taken along line 5-5 of FIG. 1. The rear and side elevational views are identical to the front elevational view of FIG. 1.
